CABINET

Albert Parmet, West Hempstead, N.Y., assignor to Par-Metal Products Corp., Long Island City, N.Y., a corporation of New York

Filed Apr. 28, 1961, Ser. No. 64,931

Term of patent 14 years

(Cl. D33—19)

FIG. 1 is a front perspective view of a cabinet, showing my new design.

FIGS. 2 and 3 are side elevational and top plan views, respectively, thereof.

FIG. 4 is an enlarged fragmentary perspective view of an upper corner of the cabinet showing the details thereof.

FIG. 5 is a fragmentary sectional view taken substantially along the line 5—5 in FIG. 4.

The rear of the cabinet is plain, while the hidden side is substantially a mirror image of the side shown.

I claim:

The ornamental design for a cabinet, as shown and described.
